Primary Examiner — Selina Sikder(74) *Attorney, Agent, or Firm* — Ward and Smith, P.A.(57) **CLAIM**

The ornamental design for a hand held controller, substantially as shown and described.

DESCRIPTION

FIG. 1 is a isometric view of an embodiment of a hand held controller showing our design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines shown in the drawing views are for illustrative purposes only forms no part of the claimed design.
